DISPENSING HOLDER FOR BOTTLES OR THE LIKE

Edwin F. Bushman, Aurora, Ill.

Application May 17, 1948, Serial No. 146,416

Term of patent 14 years

(Cl. D44—29)

To all whom it may concern:

Be it known that I, Edwin F. Bushman, a citizen of the United States and a resident of the city of Aurora, in the county of Kane and State of Illinois, have invented a new, original, and ornamental Design for a Dispensing Holder for Bottles or the like, of which the following is a specification, reference being had to the accompanying drawing, forming part thereof.

Figure 1 is a perspective view of a dispensing holder for bottles or the like in a partially opened position, showing my new design;

Figure 2 is a top view of the holder as seen when the handles are in a closed position; and,

I claim:

The ornamental design for a dispensing holder for bottles or the like, as shown and described.
EDWIN F. BUSHMAN.
